UNITED STATES PATENT OFFICE.

THOMAS D. WHITE, OF BELLEVILLE, ONTARIO, CANADA, ASSIGNOR TO ROBERT J. GRAHAM, OF BELLEVILLE, CANADA.

HYDRAULIC JACK.

Application filed January 3, 1927. Serial No. 158,626.

This invention relates to jacks of the type in which a pump contained in a handle serves to pump oil from a reservoir to an hydraulic ram, and in which the handle is hinged so that, when the ram plunger is to be lowered, the handle may be brought to a position to permit of a back flow from the ram to the reservoir.

My object in the present invention is to devise a reliable jack, which may be used in any position and in which all danger of oil leakage, when the jack is carried on its side, is eliminated.

The main features of my invention are the location of the oil reservoir, as well as the pump, in the handle of the device, the positioning of a spring actuated follower over the oil in the reservoir to follow the movements of the oil, and the provision of spring actuated air inlet and outlet valves at the upper end of the oil reservoir.

Other features of novelty will appear from the detailed description and the accompanying drawings in which

Fig. 1 is a longitudinal section of my improved jack;

Fig. 2 a longitudinal section of the oil reservoir and pump, the section being taken in a plane at right angles to Fig. 1;

Fig. 3 a cross section through the base of the oil reservoir and trunnion, on which it has a bearing showing the parts in position to form a direct connection from the ram to the oil reservoir.

In the drawings like numerals of reference indicate corresponding parts in the different figures.

1 is the base of the jack, which carries the ram, and on which is journaled the handle containing the oil reservoir and pump. The cylinder 2 of the ram is formed of a section of tube threaded into the base and provided at its upper end with a stuffing box 3, through which passes a tube 4 forming the plunger of the ram. The stuffing box holds in place the cylinder lining 2a. The plunger head or piston is of ordinary type provided with the cup-leather 5, giving the plunger an oil tight fit with the interior of the cylinder. The screw 6 is threaded through a head fitted to the plunger and is provided with a head 7 adapted to engage the part to be lifted.

On the base is formed an annular socket 8 having a tapered bore, into which is fitted a

tapered trunnion 9, the end of which is threaded for engagement by the nut 10, by means of which the trunnion may be tightly secured within the socket 8. Through the base of the socket is formed a conduit 11 communicating with the interior of the base below the plunger head. The trunnion has a passage 12 formed therethrough communicating with the conduit 11 and with a notch 13 formed in the side of the trunnion, which notch is extended through an arc approximating 90° or rather more. On this trunnion a handle is hinged forming the oil reservoir and carrying the oil pump. The reservoir comprises the base 14 and a head 15 connected by a tube 16. The base has communicating passages 17 and 18 formed therein, the passage 17 forming a communication between the pump cylinder and the opening in the base receiving the trunnion, and the passage 18 forming a communication between the passage 17 and the interior of the oil reservoir. Spring actuated valves 19 and 20 of known type and fitted in a known manner form the pump valves, the valves both opening downwardly. The pump cylinder 21 is threaded into a suitable opening in the base and its upper end fits within a sleeve 22 of the stuffing box formed on the head 15. A coil spring 23 bears against the end of the cylinder tube and the packing material in the stuffing box and serves to make a tight joint for a plunger 24, which passes through the stuffing box and down into the pump cylinder 21. The operating connections with this plunger will be hereinafter described.

25 is a relief passage formed through the base 14 at the side of the base nearest the ram and communicating with the opening in the base in which the trunnion 9 is received. With the parts in the position shown in Fig. 1, both the passage 17 and the relief passage 25 are closed by the solid part of the trunnion. It will be evident, however, that if the reservoir be swung outwardly so that the notch 13 is in communication with the inner end of the passage 17 the operation of the pump plunger 24 will cause oil to be forced through the reservoir to operate the ram. It will further be evident that if the reservoir be swung to the position shown in Fig. 3, the relief passage 25 will be brought into communication with the notch 13 and oil may then flow from beneath the ram di-

rectly to the reservoir so that pressure on the ram head 7 will cause its depression. When the parts are in the position shown in Fig. 1, any oil pumped into the ram is held there, thus maintaining the ram head in any position to which it has been raised. Into the head 15 of the oil reservoir is screwed the lower end of a tube 26 which serves as a guide for a pump handle 27, which passes through a cap 28 screwed on the upper end of the tube 26 and is provided with a hand knob 29. The plunger 24 is pinned to the tube 26, by means of the pin 30. Between the head 15 of the oil reservoir and the shoulder formed by the lower end of the tube 26 is located a coil spring 31, which serves to elastically limit the downward movement of the pump plunger.

An important feature of my invention is 20 the means provided to retain the oil in the lower part of the reservoir no matter what the position of the ram or the position of the jack is as a whole.

On the pump cylinder 21 is positioned a 25 follower comprising a head 32, on which is clamped, by means of a ring 33 and bolts 34, a leather cup-washer 35, which bears against both the exterior of the pump cylinder 21 and the interior of the wall of the 30 reservoir. A coil spring 36 bears against the follower and the head 15. This spring causes the follower to follow the oil level in the reservoir and prevents it leaking through to the upper part of the reservoir. 35 The pump and oil passages are thus always kept full of oil, so that there is no danger at any time of the pump failing to work through lack of priming after it has lain for a considerable time in a horizontal or other 40 position otherwise likely to drain the oil passages. Leakage of oil through the head 15 is also entirely prevented.

To enable the follower to readily follow the oil, it is necessary to provide an air 45 passage or passages through the head 15. While a simple breather hole would be sufficient, it is preferable to have any passage to the interior of the upper end of the oil reservoir valve controlled as an extra safe- 50 guard against leakage when the jack is laid on its side, and also to prevent dust and dirt from entering the oil chamber, hence I employ the two passages 37 through the head 15, one controlling by an inwardly open- 55 ing spring actuated valve 38 and the other by an outwardly opening valve 39. These are of known type and arranged in a known manner.

What I claim is:

60 1. An hydraulic jack comprising a ram; a trunnion fixed thereon having a single passage therethrough communicating with the

interior of the ram below the plunger thereof; and a handle hinged on the trunnion containing an oil reservoir and a pump and 65 pump valves adapted to pump oil from the reservoir through the trunnion to the ram.

2. An hydraulic jack comprising a ram; a trunnion thereon having a single passage therethrough communicating with the in- 70 terior of the ram below the plunger thereof; and a handle hinged on the trunnion containing an oil reservoir and a pump and 75 pump valves adapted to pump oil from the reservoir through the trunnion to the ram, the trunnion having a transverse passage and the handle having a passage therein adapted to form a direct connection from the ram to the reservoir through the trunnion when the handle is suitably positioned. 80

3. An hydraulic jack comprising a ram; a trunnion thereon having a passage there- 85 through communicating with the interior of the ram below the plunger thereof; an oil reservoir, forming a handle, having a base journaled on the trunnion; a pump cylin- 90 der within the reservoir; passages in the base communicating with the cylinder, the reservoir and the opening in the base for the trunnion; spring actuated inlet and out- 95 let valves in said passages; and a relief pas- sage extending from said opening to the reservoir, the openings of said passages and the passage through the trunnion being so positioned and proportioned that, in one position of the handle, the pump is in connection with the ram and in another position the reservoir is in direct connection with the ram.

4. A hydraulic jack comprising a ram; a 100 handle connected therewith containing an oil reservoir; a pump adapted to pump oil from the reservoir to the ram; and a spring actuated follower in the reservoir adapted to follow the oil. 105

5. A hydraulic jack comprising a ram; a handle connected therewith containing an oil reservoir; a pump adapted to pump oil from the reservoir to the ram having its cylinder axially arranged within the reser- 110 voir; and a spring actuated follower in the reservoir sliding on the pump cylinder and adapted to follow the oil.

6. A hydraulic jack comprising a ram; a handle connected therewith containing an oil reservoir; a pump adapted to pump oil from the reservoir to the ram; a spring actuated follower in the reservoir adapted to follow the oil; and spring-valve controlled 115 breather passages leading to the upper part of the reservoir. 120

Signed at Belleville, Ont., Can., this eleventh day of December, 1926.
